ELECTRIC RADIANT HEATER

John P. Theisen, Jacksonville, Ill., assignor to New York
Shipbuilding Corporation, New York, N. Y., a corpo-
ration of New York

Application October 18, 1954, Serial No. 32,706

Term of patent 14 years

(Cl. D81—10)

Fig. 2.

Fig. 3.

Figure 1 is a front perspective view of an electric radiant heater embodying my new design;

Figure 2 is a rear elevational view on a reduced scale.

Figure 3 is a side elevational view thereof.

I claim:

The ornamental design for an electric radiant heater, substantially as shown.
